UNITED STATES PATENT OFFICE.

CLYDE S. WRIGHT, OF TOLEDO, OHIO, ASSIGNOR TO THE NATIONAL SUPPLY COMPANY,
OF TOLEDO, OHIO, A CORPORATION OF OHIO.

ELEVATOR.

1,420,010.

Specification of Letters Patent. Patented June 20, 1922.

Application filed June 1, 1921. Serial No. 474,176.

To all whom, it may concern:

Be it known that I, CLYDE S. WRIGHT, a citizen of the United States, residing at Toledo, in the county of Lucas and State of Ohio, have invented new and useful Improvements in Elevators, of which the following is a specification.

My invention relates to elevators designed for the handling of the casings of oil and other wells, but I do not limit it to that particular use.

With elevators having a door or closure, difficulty is often experienced in closing the same when a pipe or casing is standing up in the derrick. Sometimes the door is not entirely closed, so that the pipe or casing may accidentally drop down the well and the men around the well be injured. In many elevators there is a latch extending directly from the door into the body of the elevator, wherein heavy strains due to the pipe or casing suspended on the elevator are borne by the latch which is necessarily comparatively weak. It is the object of the present invention to provide means whereby the elevator door may be readily operated without liability of the same not being fully closed and of the latch breaking. Another object is to render the closing of the door easy, even when the casing is not fully in its seat in the body of the elevator when the door is to be closed. Other objects appear hereinafter.

Referring to the accompanying drawing, Fig. 1 is a front elevation of my improved elevator with the links broken off and with a piece of casing seated in the body of the elevator, the elevator door or closure being open. Fig. 2 is a view similar to Fig. 1, but showing the door closed. Fig. 3 is a plan view of my elevator with the door open and Fig. 4, a plan view thereof with the door partially closed and with a portion of the body broken away, a casing being shown in cross-section in the elevator. Fig. 5 is a plan view of my elevator with the door fully closed and parts broken away.

On the drawing, 1 designates the body or bail member of my elevator. It has an open U-shaped opening 2, its inner portion being preferably semicircular. The body has, opposite the ends of the diameter connecting the extremities of the semi-circle, the two trunnions 3 for the reception of the ends of the usual bail 4.

The member 1 has, on its side opposite the semi-circular opening therein, the two lugs 5 and 6 forming the lateral walls for the outer or open end of the said U-shaped opening. The lug 5 is a tongue or hinge member to receive the forked members 7 of the door 8, the hinge-pin 9 extending through the lug 5 and the members 7. The face of the lug 6 opposite the lug 5 has the horizontal groove 10 to receive the reduced end 11 of the door.

The lug 6 has the slot 12 in which one end of the lever or member 13 is pivotally secured by the pin 14. The lever 13 has its inner face provided with a lug 15 arranged to engage the outer face of the end 11 of the door when the latter is near its closed position, as shown in Fig. 4, and to force the door closed when the lever is swung into contact with the outer face of the door, as shown in Fig. 5. 16 is a handle on the lever 13, and 17, a handle on the door.

When the lever 13 is nearing its closed position its free or outer end engages the outer end of the spring-actuated sliding latch 18 and presses it back until the said end of the lever passes the end of the latch, whereupon the latch is forced outwardly by its spring 19 so as to overlap the said end of the lever 13 and prevent it from accidentally opening. The latch slides beneath the edges of the lugs or guides 20 on the outer face of the door. It has the slot 21 through which the screw 22 is passed into the door to limit the throw of the latch and to prevent the spring from ejecting it from its guides 20.

When my elevator is swung so as to cause the slot or opening 2 to embrace a casing 23, as shown in Fig. 1, the part of the elevator being as best shown in Fig. 3, the operator seizes the handle 17 and swings the door 8 toward closed position. If the casing is seated against the inner end of the opening 2, the door will readily be swung to full closed position over the previously unenclosed part of the casing. Then the lever 13 will be swung to its closed position where it becomes locked, thereby locking the door closed, so as to prevent the accidental escape of the casing from the elevator. By pushing back the latch 18 and seizing the handle 16, the lever 13 may be opened, thereby releasing the door 8 which may be opened by means of the handle 17. If, however, the

casing 23 should not at first be fully seated in the opening 2, but should stand therein so as to be engaged by the door 8 before it is fully closed, as shown in Fig. 4, the lever 13 5 may be swung toward its closed position and force the door entirely to its closed position by means of its inner face or the lug 15 engaging the end 11 of the door. The lever 13 operates with powerful force on the door 8 10 which is itself a lever, the two operating together as compound levers to fully seat the casing in the elevator. The latch 18 being over the outer end of the lever 13, whose working power is applied close to its fulcrum, is subjected to but little transverse or 15 shearing strains, such as the latches are which directly lock the door to the bail members. I can use a very weak latch spring 19, which permits the latch to be retracted easily 20 by the lever 13 or by the fingers of the operator.

I claim:

1. In an elevator, a body member having an open lateral slot to receive an object, a 25 door hinged at one end to the body member to close the slot, a lever also pivoted to the body member for forcing the door to its closed position and means for locking the lever in its closed position.
2. In an elevator, a body member having an open lateral slot to receive an object, a 30 door hinged at one end to the body member to close the slot, a lever also pivoted to the

body member for forcing the door to its closed position and a spring actuated latch 35 for locking the lever in its closed position.

3. An elevator having a body member with an open slot, a door member hinged at one end to the body at one side of the slot, a lever member hinged at one end to the body at the 40 remaining side of the slot, and arranged to hold the door closed, and means carried by one of the members for locking the lever member in its door-holding position.

4. An elevator having a body member with 45 an open slot, a door member hinged at one end to the body at one side of the slot, a lever member hinged at one end to the body at the remaining side of the slot, and arranged to force the door closed and hold it closed, 50 and means carried by one of the members for locking the lever member in its door-holding position.

5. An elevator having a body member with 55 an open slot, a door member hinged at one end to the body at one side of the slot, a lever member hinged at one end to the body at the remaining side of the slot, and having a portion close to its pivot to engage the free end 60 of the door and force the latter to its closed position, and means for releasably locking the lever in the position it has when it has closed the door.

Signed at Toledo, Ohio this 9th day of May, A. D. 1921.

CLYDE S. WRIGHT.
